NEIL A. DAVIDSON, OF MINNEAPOLIS, MINNESOTA, ASSIGNOR TO BUREAU OF ENGRAVING, INC., OF MINNEAPOLIS, MINNESOTA, A CORPORATION OF MINNESOTA

DISPLAY DEVICE FOR CARTONS AND THE LIKE

Application filed April 4, 1929. Serial No. 352,450.

My invention has for its object to provide an extremely simple and highly efficient display device having means for mounting the same on a carton or the like. The display device while intended for general use is especially well adapted for use as a sign for advertising the contents of a carton or other receptacle on which the display device is mounted.

5 To the above end, generally stated, the invention consists of the novel devices and combinations of devices hereinafter described and defined in the claims.

In the accompanying drawings, which 15 illustrate the invention, like characters indicate like parts throughout the several views.

Referring to the drawings:

Fig. 1 is a perspective view of the display device mounted on a carton;

20 Fig. 2 is a view corresponding to Fig. 1 with the exception that the parts are viewed from the back;

Fig. 3 is a fragmentary view partly in side elevation and partly in section taken on the 25 line 3—3 of Fig. 2, on an enlarged scale;

Fig. 4 is a view partly in plan and partly in horizontal section taken on the line 4—4 of Fig. 3; and

Fig. 5 is a face view of a blank from which 30 the display device is formed.

In the drawings there is illustrated a carton A on which the improved display device is mounted. The display device is formed from a single sheet of cardboard or other 35 relatively stiff material and, as shown, is of substantially rectangular form with the two lower corners thereof shaped to form ogee curves. In forming the display device it is first blanked, as shown in Fig. 5, and

40 includes a body member 6 in the bottom portion of which is a notch 7 of such width as to receive the carton A with a relatively snug fit, as best shown in Fig. 1.

The stock required to form the notch 7 is 45 substantially all used, without detaching the same from the body member 6, to form certain elements required to hold the display device on the carton A in an upright position. These elements include a pair of retaining lugs 8, a base member 9, a pair of

braces 10 and a pair of anchor lugs 11. The retaining lugs 8 project into the notch 7 from the upright edges thereof and at the lower inner corners of the prongs formed by said notch. The base member 9 extends into the 55 notch 7 from its upper edge and is located at the center thereof. Formed with the upright edges of the base member 9 are the two braces 10 and the anchor lugs 11 are formed with the lower ends of said braces.

A folding line 12 is formed at the junction between the body member 6 and the base member 9 and folding lines 13 are formed between the base member 9 and the braces 10. These folding lines 12 and 13 are formed by 60 scoring or otherwise creasing the sheet. It is important to note that the folding lines 13 are in downwardly diverging relation for a purpose that will presently appear. The anchor lugs 11 are severed from the base member 9, as indicated at 14. The braces 10 at their upper edges extend the full distances between the base member 9 and the upright edges of the notch 7 and are cut away at 15 to leave feet 16 on the upper corners of said 65 braces. These braces 10, at their lower ends, and the anchor lugs 11 are in substantially the form of semi-circles and the upright edges of said braces are in upwardly diverging 70 relation.

To apply the display device to the carton A the base member 9 is first bent out of the notch 7 into a position in which it extends substantially perpendicular to the body member 6. The braces 10 are then bent laterally 75 upward on the folding lines 13 into positions in which they are substantially perpendicular to the base member 9. The movement of the braces 10 brings the anchor lugs 11 into downturned positions in which they project 80 below the base member 9. With the members 9 and 10 thus adjusted the display device is placed in a position on the carton A in which the front upper portion of said carton extends into the notch 7 and is straddled thereby. In this position of the display device on the carton A it is slightly rearwardly inclined 85 with the body member 6 at the transverse portion of the notch 7 resting on the top of the carton A slightly rearward of the front 90

95

100

face thereof and with the retaining lugs 8 overlapping and engaging the face of the carton A. The base member 9 rests on the top of the carton A with its free end flush with the back thereof and with the anchor lugs 11 engaging the back of the carton A.

Obviously the prongs of the body 9, formed by the notch 7, by their engagement with the sides of the carton A hold the display device 10 against edgewise shifting movement on said carton and the retaining lugs 8 and the anchor lugs 11 by their engagement with the front and back of the carton A, respectively, hold said device from shifting either forward or backward thereon.

The feet 16 when the braces 10 are adjusted into upright positions move through the arcs of circles having their centers at the folding lines 13 and due to the converging relation of 20 said braces their feet 16 during the raising of the braces 10 gradually approach the rearwardly inclined body member 6 until said braces have nearly reached upright position and then said feet gradually recede from said member as the braces 10 are brought into upright or slightly inwardly inclined positions. The bending of the braces 10 on the their 25 folding lines 13 into upright positions places the same under slight tension so that when 30 they are released the tendency thereof is to spring backward but they are held from doing so by the rearward pressure of the inclined body member 6 thereon and the tension on said braces is not sufficient to overcome said body member. Furthermore, when 35 the braces 10 are brought into upright positions the body member 6 is pressed forward by the feet 16 causing said body to rock on the top of the carton A and thereby swing its 40 prongs rearward which presses the retaining lugs 8 against the face of the carton A. This forward movement of the body member 6 also moves the base member 9 forward on the top of the carton A and draws its anchor lugs 45 11 against the back of said carton.

Obviously when the display device is mounted on the carton, as above described, said carton may be moved without disturbing the display device held thereon. The above 50 display device is especially well adapted for advertising the contents of cartons or the like placed in windows or on counters and the positions of the cartons may be shifted or moved from time to time without disturbing 55 the display device mounted thereon.

What I claim is:

1. A device of the class described having a bifurcated bottom portion adapting the device to straddle a carton and be supported thereon, said device having on the prongs of its bifurcated bottom portion retaining members arranged to overlap and engage the front face of the carton and having at its back a brace for holding the device upright.
2. A device of the class described having

a bifurcated bottom portion adapting the device to straddle a carton and be supported thereon, said device having on the prongs of its bifurcated bottom portion retaining members arranged to overlap and engage the front face of the carton and having at its back a brace for holding the device upright, and an anchor lug engageable with the carton at the back thereof.

3. A device of the class described formed from a single sheet of material having a notch in its bottom portion adapting the device to straddle a carton, retaining lugs on the prongs formed by said notch arranged to overlap and engage the face of the carton, a brace 75 arranged to rest on the carton and hold the device upright and an anchor lug arranged to engage the carton at the back thereof.

4. A device of the class described formed from a single sheet of material having a 85 notch in its bottom portion, a pair of retaining lugs projecting into the notch from the upright edges thereof, a base member projecting into the notch from the top thereof, a brace on the base member extending 90 into the notch, an anchor lug at the lower end of the brace, said base member being arranged to be folded into a position in which it projects out of the notch rearward from the device and permits the device to straddle 95 the carton with its retaining lugs overlapping and engaging the front face thereof and with the base member resting on the top of the carton, said brace being arranged to be turned into a position in which it engages the back 100 of the device for holding the same upright with the anchor lug extending downwardly and engaging the carton at the back thereof.

5. A device of the class described formed from a single sheet of material and having a notch in its bottom portion, a pair of retaining lugs projecting into the notch from the upright edges thereof, a base member projecting into the notch from the top thereof and having on its upright edges a pair 105 of reversely and outwardly extended braces projecting into the notch and folding lines between the braces and base member, said braces having anchor lugs on their lower ends that extend toward each other, said base member being arranged to be folded into a position in which it projects outward of the notch rearward from the device and leaves 110 said notch unobstructed and permits the device to straddle a carton with said retaining lugs overlapping and engaging the front face thereof and with the base member resting on the top of the carton, said braces being arranged to be folded on their folding lines into positions in which they engage the 115 back of the device and hold the same upright with the anchor lugs extending downwardly and engaging the carton at its back.

6. A device of the class described formed from a single sheet of material having a 120

notch in its bottom portion, a pair of retaining lugs projecting into the notch from the upright edges thereof, a base member projecting into the notch from the top thereof and having a folding line at its junction with the body of the device, said base member having on its upright edges a pair of reversely and outwardly extended braces projecting into the notch and folding lines between the braces and base member, said braces having anchor lugs on their lower ends that extend toward each other, said base member being arranged to be folded on its folding line into a position in which it projects outward of the notch and rearward from the device and leaves the notch unobstructed to permit the device to straddle a carton with the retaining lugs overlapping and engaging the front face thereof, and with the base member resting on the top of the carton, said braces being arranged when folded on their folding lines to extend upward from the base member for engagement with the back of the device to hold the same upright with the anchor lugs extending downwardly and engaging the carton at its back.

7. The structure defined in claim 6 in which the folding lines between the braces and the base member are in downwardly diverging relation.

8. The structure defined in claim 6 in which the folding lines between the braces and the base member are in downwardly diverging relation and in which the upper ends of the braces are notched to leave feet at the outer upper corners of the braces.

In testimony whereof I affix my signature.
NEIL A. DAVIDSON.
